DESIGN FOR A FAUCET

Leonard Keller, Ferndale, Mich., assignor to The Murray Corporation of America, Detroit, Mich., a corporation of Delaware

Application December 1, 1939, Serial No. 88,614

Term of patent 7 years

To all whom it may concern:

Be it known that I Leonard Keller, a citizen of the United States of America, residing in Ferndale, in the county of Oakland, State of Michigan, have invented a new, original, and ornamental Design for a Faucet of which the following is a specification, reference being had to the accompanying drawing, forming a part thereof, wherein:

Figure 1 is a plan view of the faucet showing my new design;

Fig. 2 is a side view, in elevation, of the faucet illustrated in Fig. 1; and,

Fig. 3 is a front view in elevation of the faucet illustrated in Fig. 1.

I claim:

The ornamental design for a faucet, substantially as shown.

LEONARD KELLER.
